UNITED STATES PATENT OFFICE.

HILARION DE ESCOBALES, OF NEW YORK, N. Y., ASSIGNOR TO H. ESCOBALES CO. INC.,
OF NEW YORK, N. Y., A CORPORATION OF NEW YORK.

APPARATUS FOR PRODUCING PACKAGES.

1,391,174.

Specification of Letters Patent. Patented Sept. 20, 1921.

Application filed November 26, 1917. Serial No. 203,951.

To all whom it may concern:

Be it known that I, HILARION DE ESCOBALES, a citizen of the United States, residing at New York, in the county of New York and 5 State of New York, have invented new and useful Improvements in Apparatus for Producing Packages, of which the following is a specification.

This invention relates to apparatus for 10 producing packages, pertaining more particularly to apparatus designed to apply a wrapper to the embryo package with one end of the package exposed.

Among the objects of the invention are:—

15 1. To provide an apparatus adapted to automatically fold a wrapper about the embryo package with one end of the package exposed, the wrapper having an adhesive connection with the embryo package.

20 2. To provide an apparatus adapted to apply a label or stamp over one end of the embryo package, the label or stamp ends extending over side faces of the package, and applying a wrapper to the labeled or 25 stamped package in such manner as to leave the stamped or labeled end exposed, the wrapper covering the label or stamp ends.

30 3. To provide an apparatus for these purposes adapted to automatically apply either or both to an embryo package, the apparatus having a cycle of operations which will 35 complete the desired action automatically.

35 4. To provide an apparatus which is simple and efficient in operation, durable in construction, and which can be manufactured at a comparatively low cost.

To these and other ends, the nature of 40 which will be readily understood as the invention is hereinafter disclosed, said invention consists in the improved construction and combination of parts hereinafter fully described, illustrated in the accompanying drawings, and more particularly pointed out in the appended claims.

45 In the accompanying drawings, in which similar reference characters indicate similar parts in each of the views:

50 Figure 1 is a top plan view, partly in horizontal section, showing the operating mechanism and the general arrangement and relative locations of the several instrumentalities.

Figs. 2 and 3 are detail perspective views

of two plungers employed in the wrapper folding operation.

Fig. 4 is a detail sectional view taken on line IV—IV of Fig. 5.

Fig. 5 is a longitudinal sectional view taken on line V—V of Fig. 1.

Fig. 6 is a detail sectional view taken on line VI—VI of Fig. 1.

Fig. 7 is a transverse sectional view taken on line VII—VII of Fig. 5.

Fig. 8 is a detail sectional view taken on line VIII—VIII of Fig. 5.

Fig. 9 is a view of parts shown in Fig. 8 with the elements in a different position.

Fig. 10 is a view of parts shown in Fig. 8 and showing the elements in another position.

Fig. 11 is a sectional view of blank feeding apparatus, the section being taken on line XI—XI of Fig. 7.

Figs. 12 to 17 inclusive are perspective views showing successive steps in the production of the package.

Before entering into a detail description of the structures forming the mechanism of the present invention, I will first give a brief description of the successive steps in the formation of the package, and a brief description of the general apparatus for providing the several steps.

The present invention deals more particularly with a preformed embryo package—a package which has been provided with a wrapper or other covering, preferably in loose formation—which is preferably of more or less rectangular form. The embryo package is assumed to have been prepared and delivered to the present apparatus in its prepared form. The embryo package thus produced is indicated at *a*.

In the preferred package formation, the first step is the positioning of a label or stamp—indicated at *s*—in proper relation to an end of the embryo package, this position being shown more particularly in Fig. 12, the label or stamp having an intermediate portion of its length applied to an end of the package. As the width of the label or stamp is preferably less than the package end, the location is preferably such as to place the label or stamp at an intermediate portion of the package end. In other words, 100 the direction of length of the label or stamp

105

extends practically at right angles to the direction of length of the package end, the length of one element being less than the width of the other, with the point of contact intermediate the ends of the element.

The next step is to complete the application of the label or stamp, this being provided by applying the ends of the label or stamp to opposite sides or faces of the package, thus producing the result shown in Fig. 13.

This is followed by bringing the opposite end of the stamped package into contact with a wrapper blank, preferably rectangular in form. The length of the wrapper blank is preferably—although not essentially—of a length equal to the approximate combined length of the opposite sides or faces and an end of the package, the width of the wrapper being greater than the length of the package end. As shown in Fig. 14, the contact is made substantially midway of the length and width of the wrapper blank. The wrapper blank is then folded on to the opposite sides of the package and on to the faces of the label or stamp ends, after which intermediate portions of the wrapper are infolded, producing the result of Fig. 15. This operation is followed by turning down the upper wings thus produced—forming the arrangement of Fig. 16—after which the lower wings are folded up to complete the package. As will be seen, the label or stamp as well as the wrapper blank—the latter being indicated at *w*—are provided with adhesive stripes on one face, by means of which each is adhesively secured in position. The stripes extend longitudinally and provide an efficient adhesive structure.

As will be understood, this general action practically has the effect of applying a stamp or label across one end of the embryo package, after which a more or less cup-like structure is applied about all portions of the package excepting said end, the latter being exposed with the exception of the part covered by the stamp or label, this latter being exposed. Obviously, if the stamp or label be omitted, the entire end of the package will be exposed. Hence, so far as the general operation is concerned, this package end may be considered as an exposed end whether the stamp or label be applied or not. Since the applied elements are secured in position by adhesion, the applied structures will produce conditions more or less analogous to a tight wrapped structure. This is of advantage in that while the wrapper is cup-like in formation, it is secured to the package without the use of any other holding mechanism than the adhesive with which the blank is provided, this result being obtainable by reason of the fact that the adhesive is applied to the wrapper in ad-

vance of folding, so that not only is the blank provided with the adhesive necessary to secure the folds in position with respect to the blank itself, but also to retain the folded formation fixedly on the package.

As will be understood, the several steps are such as will permit the general wrapping operation to be provided with embryo packages having various contents, the invention not being limited in this respect. For instance, the embryo package may be a cigarette package with the loose wrapping, or it may be a plug of tobacco properly loosely wrapped, these being simply examples of package contents when employed in connection with tobacco products. Obviously, other commodities may form the package contents.

The present invention is designed to produce this result through the operation of a series of instrumentalities which are made effective in a predetermined sequence, these instrumentalities being so arranged and operating in such manner that a plurality of packages may be undergoing treatment concurrently, this being made possible by a stage-like treatment, each stage providing for a certain amount of treatment, the result being that the unit of time for limiting the introduction of embryo packages—the basis for computing the capacity of the apparatus—is practically controlled by the time required for a stage operation. This will be understood from the following brief description of the operation of the apparatus:

The embryo package is located opposite a plunger reciprocating horizontally, either manually or by the operation of a conveyer structure. The plunger then operates to advance the package in the direction of its length—presenting one end in advance—bringing the advance end into contact with a positioned stamp or label, the face of the stamp or label which contacts with the package being adhesively coated. The plunger continues to advance the package and its stamp or label into an open-ended compartment formed on an endless carrier which travels intermittently in a direction transverse to the direction of advance of the package, the carrier having a plurality of compartments, each intermittent movement placing one of the compartments in the path of travel of an advancing package. The several structures are so arranged that as the package advances, the ends of the stamp are drawn on to the top and bottom faces of the package, the completion of the advance movement of the plunger leaving the package with the stamp applied in one compartment, the plunger then returning to its initial position. This may be considered as one stage.

The compartment-carrying conveyer then

moves in a direction transverse to the direction of advance of the package to a position where this package is located opposite a second plunger having its advance movement 5 in the direction opposite the direction of advance movement of the first plunger, the two plungers being located on opposite sides of the compartment-carrying conveyer. The location of the stamped or labeled package 10 in this position therefore places the stamped or labeled end in direct opposition to the advance end of the second plunger, the result being that advance of this plunger carries the package with the opposite end of the 15 package as the advance end, the advancing plunger carrying the package out of the compartment within which it had been transferred. This advance of the package brings this package end into contact with the adhesive face of the wrapper blank which extends vertically at this time, the continued movement of the package folding the upper and lower ends of the wrapper on to the upper and lower faces of the labeled or 20 stamped package, and causing projecting portions to be tucked in as the package advances, the end of the plunger movement positioning the partially wrapped package over a vertically extending well, the package 25 having the conformation shown in Fig. 15 at the end of the plunger movement. The plunger then returns to its initial position, practically completing what may be termed the second stage of the operation.

35 The delivery of the package during the second stage places it on a pair of yieldable supports above the well and beneath a pair of plungers, these plungers operating independently, the first plunger moving downward to fold the top wing, as in Fig. 16, the second plunger being operative to shift the yielding supports and open the well to the entrance of the package, both of these plungers moving downwardly, the second plunger 40 acting to carry the package past the shifted supports—which act to fold up the lower wings during this movement—and locate the completed package in the well. The plungers then return to initial position, the yielding supports moving to initial position 45 as the movement of the second plunger permits, thus completing the third stage. The well permits the gradual movement of the completed package therethrough to a suitable point of discharge.

50 The movements of the package from the time of introduction until located on the yieldable supports, is preferably on the same horizontal plane, the package moving first 55 endwise in one direction, then transverse to this direction, and then endwise in the opposite direction. The movement of the package after location on the yieldable supports is downwardly in a vertical direction at right angles to the horizontal plane.

This general operation provides for the positioning of the blanks in different stages, the label or stamp being received and applied in the first stage, and the wrapper blank received and partially applied in the 70 second stage. Obviously, this permits of the omission of the stamp or label application should it be desired to operate without this feature, simply by omitting to position a stamp or label in the first stage, so that the 75 apparatus is adapted to operate under different conditions as may be desired.

The blanks are fed into position by suitable feed mechanism of a type disclosed in companion applications, these mechanisms 80 being adapted to permit of individual feeding of blanks and the application of adhesive to a face of the blank, so that when the blanks are positioned, they are located to intersect the travel paths of the package and 85 in position to provide for the proper application of the blanks to the package.

In describing the apparatus in greater detail, I will, as far as possible, describe the parts in the order in which they are brought 90 into operation as above indicated.

Referring to the drawings, 20 designates a frame of suitable type, having a table-like top 20^a, this table being adapted to support certain operating elements together with a 95 supplemental table 20^b on which certain of the instrumentalities are mounted, table 20^b being supported on suitable standards 20^c.

Located below top 20^a is a shaft 21 forming the main shaft of the apparatus, this shaft being driven from a suitable drive source; in the drawings this is shown as a fast and loose pulley structure 22 having a gear connection with shaft 21.

23 indicates a reciprocating plunger 105 mounted in a suitable guide or guides, and normally positioned to one end of the package-receiving station, the latter of suitable arrangement which will permit of location of a package in proper position relative to 110 an open-ended casing 24, this casing being located at the opposite end of the station and in such position as will permit of the free movement of plunger 23 through the interior of the casing.

115 As pointed out, the receiving station may be of any desirable type, in so far as it will permit of proper location of the embryo package in such position that advance of plunger 23 will carry the package endwise through the channel of casing 24. A suitable support may be provided which will permit of positioning of the package manually. However, in the drawings, I have shown a conveyer structure by means of 120 which packages can be placed in proper position by simple mechanism, this arrangement permitting the structure to be operated as an auxiliary to a packaging machine, if desired. The specific embodiment is shown 125 130

as in the form of an endless carrier 25 mounted on rolls 26, the upper flight of the carrier being preferably supported in suitable manner. Supported in suitable manner, as by brackets, is a stop structure 27— which may be in the form of separate stop members located on opposite sides of the package travel path—the stop structure being so located as to stop the advancing movement of a package supported by the conveyer and moving transverse to the direction of movement of plunger 23, it being understood, of course, that conveyer 25 has its upper flight positioned to carry the package into contact with the stop structure, the package in such position being in practical alinement with the channel of casing 24. If desired, the stop structure may be made adjustable as may be found desirable.

20 The conveyer is preferably driven intermittently through a suitable drive connection between a shaft 28 presently referred to and the shaft 26^a of one of the rolls, shaft 28 being driven intermittently. While I prefer to employ this intermittent drive it will, of course, be understood that the conveyer may operate continuously, the packages simply lining up on the upper flight and slipping relative to the conveyer until plunger 23 completes its cycle of operation carrying the advance package from off the conveyer and permitting the remaining file of packages to advance until brought into contact with the stop structure. If desired 35 I may employ suitable guides 25^a for the purpose of retaining the file of packages in position.

A package is permitted to pass to this position whenever plunger 23 is in its inactive position (to the left of conveyer 25 in Fig. 1). With the package in position, the plunger advances into contact with the rear end of the package and advances the latter through casing 24 and into an open-ended 45 compartment on a traveling conveyer presently referred to, the package taking up its stamp or label while traveling through casing 24. The plunger then returns to its initial position. This reciprocating movement of the plunger is provided through 50 operative connections with shaft 21 as follows:

29 indicates a cam on shaft 21, said cam having a groove 29^a (Fig. 4) within which 55 a suitable member, such for instance as roller 30, extends, said roller being mounted on an arm or lever 31 pivotally mounted on a shaft or rod 32, the cam groove being operative to oscillate the arm or lever on its 60 pivot. 33 indicates a rack bar having its direction of length extending vertically and mounted in suitable guides, said rack bar having a link connection with the free end of arm or lever 31 beneath table top 20^a, said 65 rack bar extending through top 20^a and hav-

ing its teeth in mesh with the teeth of a pinion 34 carried by a shaft 35 below the plane of plunger 23 and extending transversely of the direction of length of said plunger. Mounted on shaft 35 is a gear 36 which is in 70 mesh with teeth formed on the under surface of plunger 23.

By this arrangement, movement of shaft 21 in the direction of the arrow in Fig. 4, will cause the free end of lever 31 to be 75 raised, thus raising rack bar 33 and operating shaft 35 through pinion 34, this movement of shaft 35 causing plunger 23 to advance through the gear connection therewith. When cam groove 29 permits lever 31 80 to move downward, the operative connections described will cause the plunger to return to its initial position. In this manner the timing of plunger movements can be 85 readily controlled by the pattern of the cam groove, so that not only can the amount of dwell of the plunger in inactive position be controlled, but the speed of travel of the plunger can also be controlled so as to provide for proper operation, the cam control 90 permitting of variations in speed if desired.

Casing 24 is provided with openings 24^a through which the stamp or label ^s is adapted to extend, the lower end of the stamp being supported in suitable manner, as indicated for instance in Fig. 5. This position of the stamp or label causes it to intersect the travel path of the advancing package, so that when the advance end of the latter comes in contact with this positioned stamp, 100 the latter is carried onward with the package, thus drawing the opposite ends of the stamp or label on to the top and bottom faces of the embryo package, the stamp being spaced from the edge of casing 24 and 105 hence the upper and lower channel walls of the casing will act to apply the stamp or label to these faces, the character of stamp or label application practically insuring that the stamp will be properly applied at the 110 end of the package.

The stamp feed mechanism may be of any suitable type, a preferred arrangement being of the general type disclosed in my companion application filed March 13, 1917, 115 Ser. No. 154,447. It may be noted that the wrapper blank feed mechanism presently referred to is preferably of similar type and may be modified along the lines disclosed in my companion application filed Sept. 13, 1917, Ser. No. 191,259. The general idea of these constructions is disclosed more particularly in Fig. 11, in which 37 designates a table for supporting the stamps or blanks in horizontal planes and in pile formation, 120 the frame for the table carrying a reciprocating advancing carriage 38 which operates to advance the lowermost blank of the pile into the throat of a band-formed flight shown as in the form of endless bands be- 130

tween which the stamp or blank is carried past an adhesive-applying mechanism 39 (the adhesive applying mechanism for the wrapper blanks being indicated at 39^a), the 5 band-formed flight being operative to feed the blanks individually and downwardly, so that the feeding action will present the stamps of blanks successively in vertical planes. In Fig. 5, I have shown the individual mechanisms for the stamp or label and for the wrapper in order to indicate the general locations when feeding devices of the type indicated are employed. As will be seen from Fig. 1, the stamps and the blanks 10 are fed on substantially the same vertical plane, the delivery points being spaced apart, the stamp delivery being in front of the blank delivery. This arrangement not only accommodates for an advantageous 15 general operation, but also enables the use, if desired, of a single drive connection between the main shaft 21 and the feeding mechanism. For instance, shaft 40 in Figs. 5 and 7 may be a shaft common in both 20 mechanisms, the several operating parts of each mechanism being operatively connected to and driven from this shaft. To operate both mechanisms, therefore, it is necessary only to provide proper drive to shaft 40, any 25 suitable operating connections being adapted for the purpose, as for instance gear connections between shaft 21 and a vertical shaft 41, the latter having a bevel gear connection with shaft 40, this being a simple arrangement. 30

Further detail description of the feeding mechanism is omitted, since the specific structures of these mechanisms are disclosed and claimed in other applications, the present disclosure pertaining more particularly 35 to the relative locations of these mechanisms.

Advance of the embryo package through casing 24, therefore serves to apply the 40 stamp or label to the advance end and to the adjacent opposite sides or faces of the package. As the package continues its movement under the action of plunger 23, it passes into an open-ended casing or compartment 42 carried by the upper flight of 45 an endless carrier 43, the latter preferably having a plurality of these casings or compartments in spaced apart arrangement in the direction of length of the carrier band. 50 As shown, the carrier band is mounted to travel in a direction transverse to the direction of advance of the package by plunger 23, the carrier band being mounted on rotatable supports 44 and 44^a, support 44 being mounted loosely on a shaft 45 located 55 above the plane of table top 20^a, support 44^a being fixedly mounted on shaft 28 here- 60 tofore referred to. Carrier 43 may be of any suitable type, but I prefer to employ a 65 carrier in the form of a thin steel band to

which casings or compartments 42 are secured.

Carrier 43 is moved intermittently so as to locate successive compartments 42 opposite casing 24 in position to receive an advancing package, the carrier dwelling in this position a sufficient length of time to permit proper receipt of the package, and then advancing to locate the succeeding compartment in this position. Any suitable drive mechanism for providing this operation to the carrier may be employed, a simple arrangement being shown more particularly in Fig. 7, in which a mechanical movement of suitable type—as for instance a Geneva stop movement—is interposed between shafts 21 and 45, the drawings showing a disk 46 carrying a flange and pin structure mounted on shaft 21, the complementary member 47 being loosely mounted 75 on shaft 45, and operatively connected to support 44 also loosely mounted on this shaft. This arrangement operates to provide the intermittent rotatory movement to support 44. The movement of this support 80 operates support 44^a through the carrier connection, the result being that shaft 28 practically rotates in unison with member 47. As heretofore pointed out, shaft 28 forms the drive shaft for carrier 25, so 85 that advance of the packages on the latter carrier is timed in synchronism with the movements of endless carrier 43.

Mounted in rear of casing 24 is a casing 48, this casing having openings 48^a for the 90 passage of the wrapper blank, the wrapper feed mechanism being located in position to feed a blank downwardly through these 95 openings so as to locate a blank in a substantially vertical plane relative to said casing.

Casing 48 is open-ended, one open end being opposite the open end of the casing or compartment 42 which has been shifted from the point where the package was received therein, the spacing of successive compartments 42 being such that when one compartment is in position relative to casing 24, the preceding compartment is opposite the channel of casing 48. As shown in Fig. 14, the wrapper has a width greater than the 100 length of an end of the package, the end of the package being intermediate the side edges of the blank. The construction for providing the proper positioning of the package relative to the blank is shown in Fig. 1 as in the form of guides 49 within the channel of casing 48 and positioned to 105 guide the package which is to be discharged from compartment 42 located opposite casing 48, the blank extending on opposite 110 sides of the travel path of the package as seen in Fig. 1.

The package is discharged from compartment 42 by means of a reciprocating plunger 115 120 125 130

50 mounted in suitable guides, this plunger, like plunger 23, having a rack tooth formation on its under face adapted to be engaged by the teeth of a gear 51 mounted 5 on shaft 52 operatively connected to shaft 35 by means of shaft 45 geared to shafts 35 and 52, the gear connections being shown as of the spiral type. In the particular form shown in the drawings, shaft 45 thus not 10 only acts to operatively connect shafts 35 and 52, but also forms a support for the carrier support 44 and member 47, the latter, as heretofore stated, being loosely mounted on the shaft. Obviously, shafts 35 and 52 15 may be operatively connected in other ways, or the drive connections between shaft 21 and gear 36 may be duplicated with respect to gear 51, the particular mechanism shown providing a simple arrangement by 20 means of which a single cam will provide the operations for both plungers 23 and 50, these plungers having their advance movements in opposite directions and concurrently through this form of mechanism.

25 Advance of plunger 50 causes it to contact with that end of the package to which the label was applied during movement of the package through casing 24, plunger 50 pushing the package out of compartment 42 30 into the channel of casing 48 between guides 49 and bringing the opposite end of the package into contact with the blank positioned in said casing. As the plunger continues its advance movement, the action of 35 the top and bottom walls of casing 48 causes the opposite ends of the blank to be folded rearwardly as the blank is drawn by the advance of the package, the package and the wrapper blank then passing into coöperative 40 relation with folders 53 of suitable type located in the channel of casing 48, the folders being shown as of the yielding type. These folders serve to turn in portions of the sides of the wrapper to produce the gusset fold 45 formation shown in Fig. 15. During the remainder of the advance movement of plunger 50, the package retains the shape shown generally in Fig. 15, upper and lower side wings being provided by this forming of the 50 gusset fold. After traversing the channel of casing 48, the package—in the form shown in Fig. 15—is moved into position over a well, presently referred to, and more particularly on to a pair of pivoted doors 54 55 located above said well, these doors normally lying in the plane corresponding to that on which the package is moving, the package passing beneath a plate 55 forming part of a plunger structure 56, this plunger being 60 shown more particularly in Fig. 2 and shown as having a pair of fingers 55^a depending from plate 55. As shown in Fig. 8, these fingers normally lie above the top face of doors 54.

65 As shown in Fig. 1, plunger 56 is located

within the walls of a plunger 57—shown in detail in Fig. 3—the rearwardly projecting walls of plunger 57 extending along the sides of plate 55. This arrangement places fingers 55^a within the space defined by the walls 70 of plunger 57, these fingers being so located so as to permit completion of the advance movement of plunger 50, the advance end of the package coming to rest either at a point spaced from these fingers or in juxtaposition 75 thereto as may be found desirable.

The normal position of plunger 57 is above the plane of the top of the package when the latter is being introduced beneath plate 55—see Fig. 8—so that the top and bottom end 80 wings of the wrapper formation freely pass into position beneath plate 55, the package being supported on doors 54, the latter being preferably spring-held. After the package reaches this position, plunger 57 is 85 moved downwardly, thus bringing its rearwardly extending walls 57^a into contact with the top wings of the wrapper conformation, the continued downward movement of these walls folding these upper wings into contact 90 with the sides of the package, as shown in Fig. 16, the completion of this operation leaving the parts in approximately the positions shown in Fig. 9. Plunger 56 then begins its downward movement, fingers 55^a becoming operative to rock doors 54 on their pivots to move said doors out of the path of the descending package, the latter being moved downwardly by the action of plate 55. Since, at the start of this downward 100 movement, the lower wings of the wrapper were unfolded and extend outward, this downward movement of the package will, through the relative movements of the package and the doors, fold these wrapper wing 105 portions so as to bring the latter into contact with the previously folded wings, the spring supports for the doors tending to provide a yielding folding action and at the same time tending to smooth the fold by reason of the friction present between the moving package and the doors.

During this latter folding operation, the fingers provide an advantageous action in that the rocking movement of the doors is 115 not made dependent upon the movement of the package itself, the door movements being provided by the fingers and not by the package.

The downward movement of plunger 56 120 continues, thus carrying the completely wrapped package into position between parallel flights of endless carriers which form the well within which the package is to be received and through which it travels in 125 suitable manner, as by the movements produced by the successive introduction of packages through the operations of the plunger. This movement of plunger 56 carries plate 55 beneath the plane of doors 54, and to re- 130

tain the latter in an open position so as to permit return of the plunger, I provide the plate with suitable upstanding members or wings 55^b which may be in the form of flanges or fingers as may be desired, the drawings indicating the structure as a flanged structure extending throughout the length of plate 55. It will be obvious, however, that a plurality of upwardly extending fingers may be employed in place of the single plate, the purpose being to retain the doors open, Fig. 10 indicating the general operation in this respect.

The movements of plungers 56 and 57 are provided by cams 58 and 59 respectively, mounted on shaft 21, the cam groove contours being shown in Fig. 7. The operative connection between each plunger and its cam is substantially similar with respect to the two plungers, each being approximately as follows:

60 indicates an arm carried at one end of a bell crank lever 61 pivotally supported by shaft or rod 32, the opposite end of said lever being connected to a vertical rod 62 carrying a cross-head 63 to which the plunger is secured. Arm 60 is adapted to straddle shaft 21, the free end of the arm carrying a roller or other form of connection which is adapted to extend into the groove of the cam with which it co-operates. As the cam rotates, arm 60 will be moved back and forth on shaft 21, thus moving bell crank lever 61 and providing vertically reciprocating movements to the plungers. The contours of the cam grooves are, of course, arranged to provide for proper timing of plunger movements relative to the general operation as well as relative to each other.

40 The flights of the well, indicated generally at 64, may be of suitable contour, a simple arrangement being the use of endless bands of the coil spring type, thus tending to provide more or less pressure on the folded wings of the wrapper during the period required to traverse the well, this time being generally such as to practically insure that the adhesive will have become properly dried by the time the package passes from the well.

As will be seen, therefore, the embryo package movements throughout the different cycles leading up to the last folding operation, are conducted on substantially a single 55 horizontal plane, the package being first moved in the direction of its length through casing 24 and into compartment 42, then moved transverse to this direction of length by movements of the compartments, then 60 again moving in the direction of its length but with the direction of advance reverse to that of the original movement, the package coming to rest beneath plate 55. Further movements of the package are the downward movement which carries it out of this

horizontal plane and into the well, at the same time completing the wrapping operation.

As will be understood, the movements of plungers 23 and 50 may take place concurrently and while carrier 43 is resting. Plungers 56 and 57 are made operative to complete operation between the time of positioning of one package beneath plate 55 and the time when a succeeding package is to be advanced by plunger 50, in this respect, it being necessary only that plate 55 shall be above the plane of the advancing package in order that the advance of the package may not be restrained in any material manner. Consequently, the capacity of the machine is only limited by the time required in completing the cycle of operation of either plunger 23 or 50 and that required to move a compartment 42 from one position to its succeeding position, an arrangement which will permit of comparatively large capacity operations, an advantageous factor in packaging operations, especially where it is desired to secure the wrapper in position by adhesive connection not only between parts of the wrapper but between the wrapper and the package itself.

As will be seen, the application of the stamp or label through its adhesive connection practically secures it throughout its length to the walls of the embryo package, the ends of the label or stamp then being further secured and covered by the application of the wrapper, leaving simply the end and the stamp or label exposed. This provides a form of package which is securely wrapped while leaving one end exposed and the cup-shaped wrapper securely positioned through its adhesive connection with the package, this effect being increased where the stamp or label is employed, in that the connection between the stamp and the wrapper aids in preventing shifting of the cup formation.

From the above description it will be seen that although the plungers are each of the reciprocating type, while the transfer carrier 43 is movable in but one direction—to advance the casings or compartments—each of these elements are operated from the same shaft, the mechanisms for controlling the time of operation and for setting into motion the operative connections are all carried by this shaft. This is brought about by the use of controlling cams which enables more or less flexibility in control by reason of the ability to employ a desired pattern for the cam groove, the result being that while the operating mechanisms are generally of simple character, timing can be controlled with nicety so as to produce maximum efficiency in operation.

While I have herein shown and described a preferred arrangement of parts for carry-

ing out the general structure and providing the desired operations, it will be readily understood that changes and variations therein may be required or found desirable to meet 5 the exigencies of use, and I desire to be understood as reserving the right to make any and all such changes or modifications therein as may be found desirable or necessary, in so far as the same may fall within 10 the spirit and scope of the invention as expressed in the accompanying claims.

Having thus described my invention, what I claim as new, is:

1. In apparatus for applying wrapping 15 elements to an embryo package, means for applying a strip of sheet material to one end of said package with a portion of said strip extending onto an adjacent side of the package, and means for applying to the 20 package a cup type wrapper with the bottom of the cup wrapper at the opposite end of the package, and with a side of the cup overlying said portion of the strip, the construction being such that the part of the strip 25 applied to the end of the package will be uncovered by said cup wrapper.

2. In apparatus for applying wrapping elements to an embryo package, means for applying a strip of sheet material to one end 30 of said package with portions of said strip extending onto opposite sides of the package, and means for applying to the package a cup type wrapper with the bottom of the cup wrapper at the opposite end of the package 35 and with side portions of the cup overlying said portions of the strip, the construction being such that the part of said strip applied to the end of the package will be uncovered by said cup wrapper.

3. In apparatus for applying wrapping 40 elements to an embryo package, means for applying a strip of sheet material to one end of said package with a portion of said strip extending onto a side of the package, and means for applying to the package a cup 45 type wrapper having a single thickness at the opposite end of the package and overlying the sides of the package and said portion of the strip, the construction being such 50 that the part of said strip applied to the end of the package will be uncovered by said cup wrapper.

4. In apparatus for applying wrapping 55 elements to an embryo package, means for applying an adhesively coated strip of sheet material to one end of said package with a portion of said strip extending onto a side of the package, and means for applying to the package a cup type wrapper having a 60 single thickness at the opposite end of the package and overlying the sides of the package and said portion of the strip, the construction being such that the part of said strip applied to the end of the package will 65 be uncovered by said cup wrapper.

5. In apparatus for applying wrapping elements to an embryo package, means for applying an adhesively coated strip of sheet material to one end of said package with a portion of said strip extending onto an adjacent side of the package, and means for applying to the package a cup type wrapper with the bottom of the cup wrapper at the opposite end of the package, and with a side of the cup wrapper overlying said portion of the strip, the construction being such that the part of the strip applied to the end of the package will be uncovered by said cup 70 wrapper. 75

6. In apparatus for applying wrapping 80 elements to an embryo package, means for applying an adhesively coated strip of sheet material to one end of said package with portions of said strip extending onto opposite sides of the package, and means for applying to the package a cup type wrapper with the bottom of the cup wrapper at the opposite end of the package and with side portions of the cup overlying said portions of the strip, the construction being such that 85 the part of said strip applied to the end of the package will be uncovered by said cup wrapper. 90

7. In apparatus for applying wrapping 95 elements to an embryo package, means for applying a strip of sheet material to one end of said package with a portion of said strip extending onto an adjacent side of the package, and means for applying to the package a cup type wrapper with the bottom of the cup 100 wrapper at the opposite end of the package, and with a single thickness of a side of the cup overlying said portion of the strip, the construction being such that the part of the strip applied to the end of the package 105 will be uncovered by said cup wrapper.

8. In apparatus for applying wrapping elements to an embryo package, means for applying a strip of sheet material to one end of said package with an end portion of said strip extending onto a side of the package, and means for applying to the package a cup type wrapper, including means for applying a single sheet to the opposite end of the package with an intermediate portion of 110 said sheet in engagement with said end, folding the end portions of said sheet against opposite sides of the package with one of said end portions overlying said strip end to form a single covering thickness for said 115 strip end, and infolding the sides of said sheet onto the remaining uncovered sides of the package to form a cup type wrapper.

9. In apparatus for applying wrapping 120 elements to an embryo package, means for applying an adhesively coated strip of sheet material to one end of said package with an end portion of said strip extending onto a side of the package, and means for applying to the package a cup type wrapper, in- 125 130

cluding means for applying a single sheet to the opposite end of the package with an intermediate portion of said sheet in engagement with said end, folding the end portions of said sheet against opposite sides of the package with one of said end portions overlying said strip end to form a single covering thickness for said strip end, and infolding the sides of said sheet onto the 10 remaining uncovered sides of the package to from a cup type wrapper.

10. In apparatus for applying wrapping elements to an embryo package, means for applying an adhesively coated strip of sheet material to one end of said package with the ends of said strip extending onto opposite sides of the package, and means for applying to the package a cup type wrapper, including means for applying a single sheet 20 to the opposite end of the package with an intermediate portion of said sheet in engagement with said end, folding the end portions of said sheet against opposite sides of the package with a single thickness in overlying relation to said strip ends, and folding the sides of said sheet against the remaining uncovered sides of the package to form a cup type wrapper.

11. In apparatus for applying wrapping elements to an embryo package, means for moving the package in opposite directions, means for applying to the package during its motion in one direction a covering element engaging said end and adjacent sides 35 of the package only, and means for applying during the motion of the package in the opposite direction another element to the second or opposite end and all the sides adjacent said end of said package only.

12. In apparatus for applying wrapping elements to an embryo package, means for advancing the package in opposite directions and in different vertical planes, means for shifting the package from one vertical 45 plane to another between successive advancing movements, means for presenting an element for application to an end of the package during package advancing movements in one direction, means for presenting another element for application to the opposite end of the package during package movements in the opposite direction, and stationary guide means including provisions located in advance of the said presented elements for controlling the path of travel of the package during its movement in the opposite directions.

13. In apparatus for applying wrapping elements to an embryo package, means for 60 advancing the package in opposite directions and in different vertical planes, means for shifting the package from one vertical plane to another between successive advancing movements, means for presenting an element for application to an end of the pack-

age during package advancing movements in one direction, means for presenting another element for application to the opposite end of the package during package movements in the opposite direction, the advancing movements of the package being in parallel directions, the package shifting movements being transverse to such vertical planes, and stationary guide means including provisions located in advance of said 70 presented elements for controlling the path of travel of the package during its movement in the opposite directions.

14. In apparatus for applying a cup-like wrapping to an embryo package, means for advancing the package, means for locating a wrapper blank in the path of advancing travel of the package, the positioned blank having a face adapted for adhesive connection with package walls and having a length 85 sufficient to cover an end and opposite face walls of the package while retaining the opposite end wall exposed, means for applying the wrapper to said walls during the package advancing movement, a temporary support for the advanced package, and means operative on the supported package for securing wrapper portions to the opposite side walls of the package to complete the cup 90 formation.

15. In apparatus for applying a cup-like wrapping to an embryo package, means for advancing the package, means for locating a wrapper blank in the path of advancing travel of the package, the positioned blank 100 having a face adapted for adhesive connection with package walls and having a length sufficient to cover an end and opposite face walls of the package while retaining the opposite end wall exposed, means for applying the wrapper to said walls during the package advancing movement, a temporary support for the advanced package, means operative on the supported package for securing wrapper portions to the opposite side walls 105 of the package, means for moving the wrapped package in a direction transverse to its direction of advance movement, said support forming a means in the path of the latter movement for completing the wrapping operation.

16. In apparatus for applying a cup-like wrapping to an embryo package, means for advancing the package, means for locating a wrapper blank in the path of advancing 120 travel of the package, the positioned blank having a face adapted for adhesive connection with package walls and having a length sufficient to cover an end and opposite face walls of the package while retaining the opposite end wall exposed, means for applying the wrapper to said walls during the package advancing movement, a temporary support for the advanced package, means 125 operative on the supported wrapped pack-

age for moving it in a direction transverse to such advancing movement, and means operative on the package intermediate its advancing and transverse movements for applying wrapper portions to the opposite side walls of the package.

17. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, a temporary support for the advanced package, and means made operative on the blank upon completion of the package advance movement and including such support for completing wrapping of the blank, said means including vertically reciprocating plungers operative in predetermined cycles.

18. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, and a vertically reciprocating plunger for shifting the package transverse to the direction of advance movement, said support being operative to fold wrapper portions during such package movements.

19. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, a vertically reciprocating plunger operative on the wrapper to partially fold it while the package is supported, and means for shifting the package relative to the support to complete folding operation.

20. In apparatus for applying a cup-like wrapping to embryo packages, means for advancing the package in a predetermined path, means for locating a wrapper blank

in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, a vertically reciprocating plunger operative on the wrapper to partially fold it while the package is supported, and means for shifting the package relative to the support to complete folding operation, said latter means coöperating with the support to shift the latter from supporting to folding position.

21. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, and means for shifting the package relative to the support to cause folding action of the wrapper by the support.

22. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, and means for shifting the package relative to the support to cause folding action of the wrapper by the support, said latter means coöperating with the support to shift the latter from supporting to folding position.

23. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the

package advance movement for completing wrapping of the blank, said means including a yieldable support for the advanced package, and a vertically reciprocating plunger for shifting the package relative to the support to cause folding action on the wrapper by the support.

24. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a yieldable support for the advanced package, and a vertically reciprocating plunger for shifting the package relative to the support to cause folding action on the wrapper by the support, said plunger having depending means active on the support to shift the latter from supporting to folding position.

25. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a pair of yieldable doors positioned to support the advanced package, and a vertically reciprocating plunger for shifting the package relative to said doors to cause folding action on the wrapper by the doors, said plunger having depending fingers adapted to contact with the doors during downward travel of the plunger to shift the doors from supporting to folding position.

26. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a pair of yieldable doors positioned to

support the advanced package, and a vertically reciprocating plunger for shifting the package relative to said doors to cause folding action on the wrapper by the doors, said plunger carrying means for shifting the doors from supporting to folding position and for maintaining the doors in such position during shifting of the package past the doors.

27. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a pair of yieldable doors positioned to support the advanced package, and a vertically reciprocating plunger for shifting the package relative to said doors to cause folding action on the wrapper by the doors, said plunger having depending fingers adapted to contact with the doors during downward travel of the plunger to shift the doors from supporting to folding position, said plunger being normally positioned to one side of the supporting plane of the doors and carrying means for shifting the doors from supporting to folding position and for maintaining the doors in such position during shifting of the package past the doors, said latter means being operative to prevent return of the doors to supporting position in advance of plunger movements to carry the latter to said side of the supporting plane of the doors.

28. In apparatus for applying a cup-like wrapping to embryo packages, means for advancing the package in a predetermined path, means for locating a wrapper blank in the travel path of the package, the positioned blank having a face adapted for adhesive connection with package walls, the advancing movement of the package applying the blank to an end and opposite face walls of the package, and means made operative on the blank upon completion of the package advance movement for completing wrapping of the blank, said means including a pair of yieldable doors positioned to support the advanced package, and a vertically reciprocating plunger for shifting the package relative to said doors to cause folding action on the wrapper by the doors, said plunger being normally positioned to one side of the supporting plane of the doors, said plunger carrying depending fingers and upstanding wings coöperative with the doors during the reciprocating

movements of the plunger to shift the doors from supporting to folding positions and prevent return movement of the doors in advance of movement of the plunger to 5 said side of the supporting plane.

29. In apparatus for applying a cup-like wrapping to embryo packages and wherein the wrapper is adapted for adhesive connection with package walls and the wrapper 10 blank is located relative to predetermined walls of the package by advancing movements of the package, a temporary support for the advanced package, means for completing wrapper application, said means 15 including a pair of vertically reciprocating plungers, one of said plungers extending within and being movable relatively to the other plunger.

30. In apparatus for applying a cup-like 20 wrapping to embryo packages and wherein the wrapper is adapted for adhesive connection with package walls and the wrapper blank is located relative to predetermined walls of the package by advancing movements of the package, a temporary support 25 for the advanced package, means for completing wrapper application, said means including a pair of vertically reciprocating plungers movable relatively to each other, 30 one of said plungers extending within and having its active movements in succession to the wrapper folding movements of the other plunger.

31. In apparatus for applying a cup-like 35 wrapping to embryo packages and wherein the wrapper is adapted for adhesive connection with package walls and the wrapper blank is located relative to predetermined walls of the package by advancing movements of the package, a temporary support 40 for the advanced package, means for completing wrapper application, said means including a pair of vertically reciprocating plungers movable relatively to each other, 45 one of said plungers having a pair of walls active in wrapper folding.

32. In apparatus for applying a cup-like 50 wrapping to embryo packages and wherein the wrapper is adapted for adhesive connection with package walls and the wrapper blank is located relative to predetermined walls of the package by advancing movements of the package, a temporary support 55 for the advanced package, means for completing wrapper application, said means including a pair of vertically reciprocating plungers movable relatively to each other, one of said plungers having a pair of walls active in wrapper folding, the other plunger 60 being movable between said walls.

33. In apparatus for applying a cup-like 65 wrapping to embryo packages and wherein the wrapper is adapted for adhesive connection with package walls and the wrapper blank is located relative to predetermined

walls of the package by advancing movements of the package, a temporary support for the advanced package, means for completing wrapper application, said means including a pair of vertically reciprocating 70 plungers movable relatively to each other, one of said plungers having a pair of walls active in wrapper folding, the other plunger extending between said walls and having its active movements in succession to the wall 75 movements in folding the wrapper.

34. In apparatus for applying a cup-like wrapping to embryo packages and wherein the wrapper is adapted for adhesive connection with package walls and the wrapper 80 blank is located relative to predetermined walls of the package by advancing movements of the package, a temporary support for the advanced package, means for completing wrapper application, said means including a pair of vertically reciprocating 85 plungers movable relatively to each other, one of said plungers having a pair of walls active in wrapper folding, the other plunger being movable to shift the package from between said walls after the latter have completed their folding action.

35. In apparatus for applying a cup-like wrapping to embryo packages and wherein the wrapper is adapted for adhesive connection with package walls and the wrapper blank is located relative to predetermined 95 walls of the package by advancing movements of the package, a temporary support for the advanced package, means for completing wrapper application, said means including a pair of vertically reciprocating 100 plungers movable relatively to each other, one of said plungers having a pair of walls active in wrapper folding, the other plunger extending between said walls and being movable to shift the package from between said 105 walls after the latter have completed their folding action.

36. In apparatus for applying a cup-like 110 wrapping to embryo packages and wherein the wrapper is adapted for adhesive connection with package walls and the wrapper blank is located relative to predetermined walls of the package by advancing movements of the package, means for completing 115 wrapper application, said means including a yieldable support structure for the advanced package, and a pair of vertically reciprocating plungers normally positioned to permit free location of a package on the support, one of said plungers being operative to provide folding operations while the package is so supported, the other of said plungers being operative to move the support structure 120 into position relative to a package travel path to function as folding elements for a passing package while so positioned.

37. In apparatus for applying a cup-like 125 wrapping to embryo packages and wherein 130

- the wrapper is adapted for adhesive connection with package walls and the wrapper blank is located relative to predetermined walls of the package by advancing movements of the package, means for completing wrapper application, said means including a yieldable support structure for the advanced package, and a pair of vertically reciprocating plungers normally positioned to permit free location of a package on the support, one of said plungers being operative to provide folding operations while the package is so supported, the other of said plungers being operative to move the support structure into position relative to a package travel path to function as folding elements for a passing package while so positioned, said latter plunger being also operative to move the package in such travel path.

38. In apparatus for applying a cup-like wrapping to embryo packages and wherein the wrapper is adapted for adhesive connection with package walls and the wrapper blank is located relative to predetermined walls of the package by advancing movements of the package, means for completing wrapper application, said means including a yieldable support structure for the advanced package, and a pair of vertically reciprocating plungers normally positioned to permit free location of a package on the support, one of said plungers being operative to provide folding operations while the package is so supported, the other of said plungers being operative to move the support structure into position relative to a package travel path to function as folding elements for a passing package while so positioned, said latter plunger being also operative to move the package in such travel path, the package and support structure movements being concurrent.

39. In apparatus for applying a cup-like wrapping to embryo packages and wherein the wrapper is adapted for adhesive connection with package walls and the wrapper blank is located relative to predetermined walls of the package by advancing movements of the package, means for completing wrapper application, said means including a yieldable support structure for the advanced package, and a vertically reciprocating plunger normally positioned to permit free location of a package on the support, said plunger being operative to move the support structure into position relative to a package travel path to function as a folding instrumentality for a passing package while so positioned and being also operative to move the package in such travel path.

40. In apparatus for applying a cup-like wrapping to embryo packages and wherein the wrapper is adapted for adhesive connection with package walls and the wrapper blank is located relative to predetermined walls of the package by advancing movements of the package, means for completing wrapper application, said means including a yieldable support structure for the advanced package, and a vertically reciprocating plunger normally positioned to permit free location of a package on the support, said plunger being operative to move the support structure into position relative to a package travel path to function as a folding instrumentality for a passing package while so positioned and being also operative to move the package in such travel path.

41. In apparatus for applying wrapping elements to embryo packages, independent stations for the presentation of the several elements in the path of travel of an advancing package, said stations being located at spaced points in the package travel path, stationary package guiding means including channels located in advance of the said stations, means adjacent said channels for applying elements in predetermined relation to the package during package advancing movements, and means for advancing the package through the several stations, said means including a pair of plungers individually active with respect to the several stations and successively active on the package to propel it along said channels, said plungers having their advancing movements in opposite directions, and means operative to transfer the advanced package of one plunger to position in the path of travel of the other plunger.

42. In apparatus for applying wrapping elements to embryo packages, independent stations for the presentation of the several elements in the path of travel of an advancing package, said stations being located at spaced points in the package travel path, stationary package guiding means including channels located in advance of the said stations, means adjacent said channels for applying elements in predetermined relation to the package during package advancing movements, and means for advancing the package through the several stations, said means including a pair of plungers individually active with respect to the several stations and successively active on the package to propel it along said channels, said plungers having their advancing movements in opposite directions, and means positioned to receive the package advanced by one plunger and movable to position the package in the path of travel of the other plunger.

43. In apparatus for applying wrapping elements to embryo packages, independent stations for the presentation of the several elements in the path of travel of an advancing package, said stations being located at spaced points in the package travel path, stationary package guiding means including channels located in advance of the said stations, means adjacent said channels for applying elements in predetermined relation to the package during package advancing movements, and means for advancing the package through the several stations, said means including a pair of plungers individually active with respect to the several stations and successively active on the package to propel it along said channels, said plungers having their advancing movements in opposite directions, and means positioned to receive the package advanced by one plunger and movable to position the package in the path of travel of the other plunger.

ing package, said stations being located at spaced points in the package travel path, means for applying elements in predetermined relation to the package during package advancing movements, and means for advancing the package through the several stations, said means including a pair of plungers individually active with respect to the several stations and successively active on the package, said plungers having their advancing movements in opposite directions, and an endless carrier having a plurality of spaced apart casings and having its direction of movement transverse to the direction of plunger movements, said carrier being adapted to position a casing to receive a package advanced by one plunger and to shift the casing and its contained package to position in the travel path of the other plunger.

44. In apparatus for applying wrapping elements to embryo packages, independent stations for the presentation of the several elements in the path of travel of an advancing package, said stations being located at spaced points in the package travel path, means for applying elements in predetermined relation to the package during package advancing movements, and means for advancing the package through the several stations, said means including a pair of plungers individually active with respect to the several stations and successively active on the package, said plungers having their advancing movements in opposite directions, and an endless carrier having a plurality of spaced apart casings and having its direction of movement transverse to the direction of plunger movements, said carrier being adapted to position a casing to receive a package advanced by one plunger and to shift the casing and its contained package to position in the travel path of the other plunger, said casings being open-ended to permit free passage of a plunger therethrough.

45. In apparatus for applying wrapping elements to embryo packages, independent stations for the presentation of the several elements in the path of travel of an advancing package, said stations being located at spaced points in the package travel path, means for applying elements in predetermined relation to the package during package advancing movements, stationary package guiding means including channels located in advance of said stations, and means for advancing the package through the several stations along said channels, said means including a pair of reciprocating plungers having their advancing movements in opposite directions and moving in different vertical planes, each plunger being adapted to advance a package through one of said stations, and means operative to transfer

the advanced package of one plunger to position in the path of travel of the other plunger.

46. In apparatus for applying wrapping elements to embryo packages, independent stations for the presentation of the several elements in the path of travel of an advancing package, said stations being located at spaced points in the package travel path, means for applying elements in predetermined relation to the package during package advancing movements, stationary package guiding means including channels located in advance of said stations, and means for advancing the package through the several stations along said channels, said means including a pair of reciprocating plungers having their advancing movements in opposite directions and concurrently, each plunger being individually active with respect to a station with the pair of plungers successively active on the package, and means operative to transfer the advanced package of one plunger to position in the path of travel of the other plunger.

47. In apparatus for applying wrapping elements to embryo packages, independent stations for the presentation of the several elements in the path of travel of an advancing package, said stations being located at spaced points in the package travel path, means for applying elements in predetermined relation to the package during package advancing movements, stationary package guiding means including channels located in advance of said stations, and means for advancing the package through the several stations along said channels, said means including a pair of reciprocating plungers operatively connected to move in unison and individually active with respect to the several stations and successively active on the package, said plungers having their advancing movements in opposite directions, and means operative to transfer the advanced package of one plunger to position in the path of travel of the other plunger.

48. In apparatus for applying wrappings to embryo packages, means for advancing the package to apply the wrapping, said means including a pair of plungers, and mechanism for reciprocating said plungers, said mechanism including a shaft operatively connected to each of said plungers and carrying a gear, a constantly driven cam and its drive shaft, a lever oscillated by said cam, and a rack co-operating with said gear and adapted to be reciprocated by the lever movements.

49. In apparatus for applying wrappings to embryo packages, means for advancing the package to apply the wrapping, said means including a pair of plungers having their advancing movements in opposite directions, and mechanism for reciprocating

- 5 said plungers, said mechanism including a shaft operatively connected to each of said plungers and carrying a gear, a constantly-driven cam and its drive shaft, a lever oscillated by said cam, and a rack coöperating with said gear and adapted to be reciprocated by the lever movements.
50. In apparatus for applying wrappings to embryo packages, means for advancing the package to apply the wrapping, said means including a pair of plungers, and mechanism for reciprocating said plungers, said mechanism including a shaft carrying a gear, a constantly-driven cam and its drive shaft, a lever oscillated by said cam, a rack coöperating with said gear and adapted to be reciprocated by the lever movements, and means for operatively connecting said gear carrying shaft with the plungers, said connecting means being operative to provide the advancing movement of the several plungers concurrently and in opposite directions.
51. In apparatus for applying wrappings to embryo packages, means for advancing the package to apply the wrapping, said means including a pair of plungers, and mechanism for reciprocating said plungers, said mechanism including a shaft carrying a gear, a constantly-driven cam and its drive shaft, a lever oscillated by said cam, a rack coöperating with said gear and adapted to be reciprocated by the lever movements, and means for operatively connecting said gear carrying shaft with the plungers, said connecting means being operative to provide movements of the several plungers of substantially equal length and concurrently with the plunger advancing movements in opposite directions.
- 40 52. In apparatus for applying wrappings to embryo packages, means for advancing the package to apply the wrapping, said means including a pair of plungers, and mechanism for reciprocating said plungers, said mechanism including a shaft carrying a gear, a constantly-driven cam and its drive shaft, a lever oscillated by said cam, a rack coöperating with said gear and adapted to be reciprocated by the lever movements, and means for operatively connecting said gear carrying shaft with the plungers, said connecting means being operative to provide the advancing movement of the several plungers concurrently and in opposite directions, said connections including a rack face carried by each plunger, and gears within the connections coöperating with said rack faces.
53. In apparatus for applying wrapping elements to embryo packages, a receiving station for the package, independent stations for the presentation of the several wrapping elements, each presentation station being located in advance of element folding instrumentalities, and means for advancing the package from the receiving station through the presentation stations and folding instrumentalities successively, said means including a reciprocating plunger movable through the receiving and one of the presentation stations to advance the package to apply one of the elements, a carrier for receiving the advanced package and transferring it to position in advance of the succeeding presentation station, a plunger operative to discharge the package from the carrier and movable through the latter presentation station to apply another element to the package, and stationary guide means including provisions located in advance of the said presentation station for controlling the path of travel of the package during engagement of the latter plunger therewith, the direction of transfer movement of the advanced package maintaining the latter against reversal in position of the upper and lower faces of the package.
54. In apparatus for applying wrapping elements to embryo packages, a receiving station for the package, independent stations for the presentation of the several wrapping elements, each presentation station being located in advance of element folding instrumentalities, and means for advancing the package from the receiving station through the presentation stations and folding instrumentalities successively, said means including a reciprocating plunger movable through the receiving and one of the presentation stations to advance the package to apply one of the elements, a carrier for receiving the advanced package and transferring it to position in advance of the succeeding presentation station, and a plunger operative to discharge the package from the carrier and movable through the latter presentation station to apply another element to the package, said plungers having their movements in substantially the same horizontal plane.
55. In apparatus for applying wrapping elements to embryo packages, a receiving station for the package, independent stations for the presentation of the several wrapping elements, each presentation station being located in advance of element folding instrumentalities, and means for advancing the package from the receiving station through the presentation stations and folding instrumentalities successively, said means including a reciprocating plunger movable through the receiving and one of the presentation stations to advance the package to apply one of the elements, a carrier for receiving the advanced package and transferring it to position in advance of the succeeding presentation station, a plunger operative to discharge the package from the carrier and movable through the latter presentation station to apply another element to the package, stationary guide means including provisions located in advance of the said presentation station for controlling the path of travel of the package during engagement of the latter plunger therewith, the direction of transfer movement of the advanced package maintaining the latter against reversal in position of the upper and lower faces of the package.

latter presentation station for controlling the path of travel of the package during engagement of the latter plunger therewith, said plungers having their advancing movements 5 in opposite directions.

56. In apparatus for applying wrapping elements to embryo packages, a receiving station for the package, independent stations for the presentation of the several 10 wrapping elements, each presentation station being located in advance of element folding instrumentalities, and means for advancing the package from the receiving station through the presentation stations and 15 folding instrumentalities successively, said means including a reciprocating plunger movable through the receiving and one of the presentation stations to advance the package to apply one of the elements, a carrier 20 for receiving the advanced package and transferring it to position in advance of the succeeding presentation station, a plunger operative to discharge the package from the carrier and movable through the latter presentation station to apply another element to the package, stationary guide means including provisions located in advance of the said latter presentation station for controlling the path of travel of the package during engagement 25 of the latter plunger therewith, said plungers having their movements in different vertical planes.

57. In apparatus for applying wrapping elements to embryo packages, a receiving 30 station for the package, independent stations for the presentation of the several wrapping elements, each presentation station being located in advance of element folding instrumentalities, and means for advancing the package from the receiving station through the presentation stations and 35 folding instrumentalities successively, said means including a reciprocating plunger movable through the receiving and one of the presentation stations to advance the package to apply one of the elements, a carrier 40 for receiving the advanced package and transferring it to position in advance of the succeeding presentation station, and a plunger operative to discharge the package from the carrier and movable through the latter presentation station to apply another element to the package, said plungers having their advancing movements in opposite directions and in substantially the same horizontal plane.

58. In apparatus for applying wrapping elements to embryo packages, a receiving 45 station for the package, independent stations for the presentation of the several wrapping elements, each presentation station being located in advance of element folding instrumentalities, and means for advancing the package from the receiving station through the presentation stations and 50

folding instrumentalities successively, said means including a reciprocating plunger movable through the receiving and one of the presentation stations to advance the package to apply one of the elements, a carrier 55 for receiving the advanced package and transferring it to position in advance of the succeeding presentation station, and a plunger operative to discharge the package from the carrier and movable through the latter presentation station to apply another element to the package, said plungers being movable in parallel vertical planes with the movements in substantially the same horizontal plane, the advancing movements being 60 in opposite directions.

59. In apparatus for applying wrapping elements to embryo packages, a receiving station for the package, independent stations for the presentation of the several 65 wrapping elements, each presentation station being located in advance of element folding instrumentalities, and means for advancing the package from the receiving station through the presentation stations and folding instrumentalities successively, said means including a reciprocating plunger movable through the receiving and one of the presentation stations to advance the package to apply one of the elements, a carrier 70 for receiving the advanced package and transferring it to position in advance of the succeeding presentation station, and a plunger operative to discharge the package from the carrier and movable through the latter presentation station to apply another element to the package, said plungers having their advancing movements concurrently and 75 in substantially equal length.

60. In apparatus for applying wrapping elements to embryo packages, applying instrumentalities extending in different vertical planes, means for advancing a package through said instrumentalities successively, said means including a pair of reciprocating 80 plungers having their advancing movements in opposite directions and located in the respective planes of the instrumentalities, a transfer carrier for shifting a package from one instrumentality plane to that of a succeeding instrumentality, said carrier having a plurality of package-receiving compartments to permit concurrent location of a compartment opposite each of the instrumentalities, and means for operating said 85 plungers and said carrier, said latter means including a drive shaft, operative connections between said shaft and the plunger for providing reciprocating movements to the plunger intermittently, and operative connections between said shaft and the transfer carrier for providing carrier advancing movements intermittently.

61. In apparatus for applying wrapping elements to embryo packages, applying in- 90

- strumentalities extending in different vertical planes, means for advancing a package through said instrumentalities successively, said means including a pair of reciprocating 5 plungers having their advancing movements in opposite directions and located in the respective planes of the instrumentalities, a transfer carrier for shifting a package from one instrumentality plane to that of a succeeding 10 instrumentality, said carrier having a plurality of package-receiving compartments to permit concurrent location of a compartment opposite each of the instrumentalities, and means for operating said 15 plungers and said carrier, said latter means including a drive shaft, operative connections between said shaft and the plunger for providing reciprocating movements to the plunger intermittently, and operative connections 20 between said shaft and the transfer carrier for providing carrier advancing movements intermittently and in timed relation to the plunger movements.
62. In apparatus for applying wrapping 25 elements to embryo packages, applying instrumentalities extending in different vertical planes, means for advancing a package through said instrumentalities successively, said means including a pair of reciprocating 30 plungers having their advancing movements in opposite directions and located in the respective planes of the instrumentalities, a transfer carrier for shifting a package from one instrumentality plane to that of a succeeding 35 instrumentality, and means for operating said plunger and said carrier, said latter means including operative connections between said plunger to cause plunger movements in unison, a drive shaft 40 carrying a cam, means whereby cam movements will provide plunger movements at timed intervals, and an intermittent-motion device operatively connecting said drive shaft and the transfer carrier.
- 45 63. In apparatus for applying wrapping elements to embryo packages, applying instrumentalities extending in different vertical planes, means for advancing a package through said instrumentalities successively, said means including a pair of reciprocating 50 plungers having their advancing movements in opposite directions and located in the respective planes of the instrumentalities, a transfer carrier for shifting a package 55 from one instrumentality plane to that of a succeeding instrumentality, and means for operating said plunger and said carrier, said latter means including operative connections between said plunger to cause plunger 60 movements in unison and in opposite directions, a drive shaft carrying a cam, means whereby cam movements will provide plunger movements at timed intervals, and an intermittent-motion device operatively
- connecting said drive shaft and the transfer carrier. 65
64. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being 70 positioned to present the elements of different stations on substantially the same vertical plane. 75
65. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being positioned to present the elements of different stations on substantially the same vertical plane. 80
66. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being positioned to present the elements of different stations on substantially the same vertical plane, said plane extending 85 transverse to the directions of travel of the package through the stations. 90
67. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being positioned to present the elements of different stations on substantially the same vertical plane, and means operative 95 at said stations for successively presenting elements at each station in timed sequence. 100
68. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being positioned to present the elements of different stations on substantially the same vertical plane, and means operative 105 at said stations for successively presenting elements at each station in timed sequence. 110
69. In apparatus for applying wrapping elements to embryo packages, means for advancing a package in a predetermined travel path, independent stations within such travel path for the presentation of wrapping elements to the advancing package, each station being positioned in advance of applying instrumentalities operative on the element so presented, said stations being positioned to present the elements of different stations on substantially the same vertical plane, and means operative 115 at said stations for successively presenting elements at each station in timed sequence, said latter means including individual presenting mechanisms for each station, and drive connections therefor common to the several mechanisms. 120
- In testimony whereof I have hereunto set my hand. 125

HILARION DE ESCOBALLES.
